W. O. McDIVITT.
IRONING BOARD.
APPLICATION FILED SEPT. 9, 1916.

1,242,461.

Patented Oct. 9, 1917.

UNITED STATES PATENT OFFICE.

WILLIAM OREN McDIVITT, OF BOVINA, NEW YORK.

IRONING-BOARD.

1,242,461.

Specification of Letters Patent.

Patented Oct. 9, 1917.

Application filed September 9, 1916. Serial No. 119,276.

To all whom it may concern:

Be it known that I, WILLIAM O. McDIVITT, a citizen of the United States, residing at Bovina, in the county of Delaware and State of New York, have invented certain useful Improvements in Ironing-Boards, of which the following is a specification, reference being had therein to the accompanying drawing.

10 The invention relates to ironing boards, and more particularly to the class of adjustable ironing boards.

The primary object of the invention is the provision of an ironing board of this character wherein the leg thereof serves to automatically clamp the board in horizontal position to a table top, or other support, and said leg carries an adjustable floor grip, or cleat, thereby enabling the board to be 20 clamped to tables of different heights, or other supports.

Another object of the invention is the provision of an ironing board of this character wherein the construction thereof is 25 novel in form, so that it can be readily clamped to a table top or other support, and held in proper position for use.

A further object of the invention is the provision of an ironing board of this character wherein the ironing board is reinforced 30 to avoid splitting thereof, and it can be clamped to different thicknesses of table tops.

A still further object of the invention is 35 the provision of an ironing board of this character which is extremely simple in construction, thoroughly reliable, and efficient in operation, strong, durable, and inexpensive to manufacture.

40 With these and other objects in view, the invention consists in the construction, combination, and arrangements of parts, as will be hereinafter fully described, illustrated in the accompanying drawing, and pointed out 45 in the claim hereunto appended.

In the accompanying drawing:—

Figure 1 is a fragmentary side elevation of a table showing the ironing board constructed in accordance with the invention 50 applied.

Fig. 2 is a fragmentary, vertical, longitudinal, sectional view through an ironing board.

55 Fig. 3 is a perspective view of the leg detached from the board.

Fig. 4 is a perspective view of the board detached looking toward its under face showing the leg in folded position.

Similar reference characters indicate corresponding parts throughout the several views in the drawing.

Referring to the drawing in detail, A designates a portion of the top of a table, which is of the ordinary well-known construction, and is merely shown to illustrate 65 the application of the ironing board hereinafter fully described.

The ironing board comprises a main board section 5 which tapers from one end toward the other thereof, and the narrower end is 70 preferably rounded as at 6, while the opposite wider end has formed therein a longitudinally disposed slot 7, the same being centrally located, and opens through the wider end of said section, while secured in 75 any suitable manner to the under face of the board section 5 longitudinally thereof, is a reinforcing section 8 which tapers both in width and thickness from the wider end of the board section 5 to the narrow end 80 thereof.

The reinforcing section 8 is slotted at 9 correspondingly to the slot 7 in the board section 5, and in the slots 7 and 9 are received a curvilinear leg or prop 10, which 85 has its upper end 11 curved in a reverse direction to the lower end thereof, and forms a jaw terminal 12, the leg being supported upon a pivot 13 which is passed transversely through the reinforcing section 8, for swinging 90 connecting the said leg thereto, so that when the ironing board is to be used the board section 5 at its wider end is extended beneath the table top A, and the jaw terminal 12 will engage with the upper face of 95 the table top A for the clamping of the ironing board thereto.

The lower curved end of the leg or prop 10 is formed at intervals with transversed holes 14 in any one of which is adapted to 100 be received the removable pin 15, which detachably fastens upon the leg or prop 10 the floor cleat or shoe 16, which is formed with a tread base 17, and spaced side cheeks 18 through which are passed the pin 15 centrally thereof, so that the leg or prop 10 will have a slight rocking movement in the shoe, and by adjustment of the latter upon the leg, the board section 5 can be brought 105 to a proper level relative to the table top. 110

Also by the adjustment of the shoe or cleat upon the leg or prop 10, the ironing board can be clamped to tables of different heights.

5 It is of course understood that the ironing board can be clamped to any other article or furniture, or support having a ledge, so that the board section 5 of the jaw terminal 12 can grip the same.

10 It will be observed that the particular shape of the leg balances the board section 5 should the table or other support fail to rest evenly upon the floor or foundation, and also by pressure upon the board section 5, 15 the jaw terminal 12 will firmly clamp the said section to the table or other support.

From the foregoing, it is thought that the construction and manner of operation of the ironing board will be clearly understood, 20 and therefore, a more extended explanation has been omitted.

Copies of this patent may be obtained for five cents each, by addressing the "Commissioner of Patents, Washington, D. C."

What is claimed is:—

In a device of the kind described, in combination, a main board section having a longitudinally disposed slot, a pivot pin spanning the walls of said slot, a supporting leg fulcrumed upon said pivot and having a relatively long portion adjacent one side of said pivot formed substantially segmental and a shorter portion adjacent the opposite side of said pivot curving in an opposite direction to said longer portion and terminating in a forwardly projecting rounded jaw, said segmental portion of said leg having a plurality of openings at its lower end, a floor cleat consisting of a tread base and side cheeks, and a pivot pin secured centrally in said cheeks and passing through one opening of said segmental portion of said leg.

In testimony whereof I affix my signature. 40

WILLIAM OREN McDIVITT.
